UNITED STATES PATENT OFFICE.

ANKER PETERSEN, OF WINTHROP, MASSACHUSETTS, ASSIGNOR TO THE PETERSEN CIRCULAR LOOM COMPANY, OF BOSTON, MASSACHUSETTS, A CORPORATION OF MAINE.

WINDING MACHINE.

1,081,986.

Specification of Letters Patent. Patented Dec. 23, 1913.

Application filed July 6, 1909. Serial No. 506,060.

To all whom it may concern:

Be it known that I, ANKER PETERSEN, a citizen of the United States, residing at Winthrop, county of Suffolk, State of Massachusetts, have invented an Improvement in Winding Machines, of which the following description, in connection with the accompanying drawing, is a specification, like letters on the drawing representing like parts.

This invention relates to a machine for winding bobbins, and has for its object to provide novel mechanism for giving the thread guide its rising and falling movement thereby to properly lay the thread on the bobbin; to provide a novel form of tension for the thread whereby the latter will be laid on the bobbin with a uniform tension regardless of whether it is being wound on a part of the bobbin of small or large diameter; and to otherwise improve the construction, all as will be more fully hereinafter described and then pointed out in the appended claims.

In the drawings wherein I have illustrated one embodiment of my invention, Figure 1 is a front view of a machine embodying the novel features above described; Fig. 2 is a side view; Fig. 3 is a top plan view; Fig. 4 is an enlarged sectional view through the presser-roll; Fig. 5 is a section on the line $x-x$, Fig. 4; Fig. 6 is an enlarged section on the line $y-y$, Fig. 1; Fig. 7 is a detail of the stopping mechanism; Fig. 8 is a detail of the tension.

The spindles 3 on which the yarn mass m is wound are supported in suitable bearings carried by a main frame 31 which may have any suitable or usual construction. Each spindle carries at its lower end a friction disk 32 which is adapted to rest on and be frictionally driven by a whirl 33 that is suitably sustained on a stud shaft 34 carried by the frame 31. The end of each spindle 3 projects down through the friction disk 32 thereon and is adapted to set into the upper end of the opening in the whirl 33 in which the stud 34 is received. Each whirl, therefore, not only supports its spindle but acts as a means for centering the lower end of the spindle. The whirls are driven in usual manner by belts 4 that extend over driving pulleys 35 sustained by the driving shaft 5.

The yarn or thread t is laid on the bobbin 55 by means of a thread guide 7 which is given a traverse in a vertical direction and which at the same time is gradually elevated so as to lay the yarn after the manner of the well known "filling wind". The thread guides 60 are sustained by a rising and falling frame 8 which is guided in its movement by suitable guides 37 formed on the frame 31. The frame 8 has extending from opposite sides thereof two arms 13 each of which carries at 65 its end a roll 38 that is engaged by a cam 12 fast on a cam shaft 11. The two cam shafts 11 are sustained in suitable bearings 39 and each has thereon a worm gear 10 which meshes with and is driven by a worm 9 formed on the driving shaft 5. This gearing is so timed as to give the frame 8 its rising and falling movement at proper intervals. One advantage of this construction is that the cams 12 act directly on arms rigid with the 75 frame 8 and the motion from the cams to the frames is not imparted through flexible or other yielding connections which are less liable to give accurate and true movement than is the direct connection herein shown. 80 It will be understood, of course, that the weight of the frame is sufficient to cause it to descend and to keep the rolls 38 in contact with the cams 12.

The frame 8 has a rising and falling movement through a fixed distance and the necessary gradual elevation of the thread guide for laying the thread after the manner of the well known filling wind is accomplished by the usual presser or friction wheels 30 85 which have a screw-threaded engagement with rods 40 carried by the frame. In the construction herein shown these presser wheels 30, which are preferably made of wood, fiber, or similar material, and which 90 are provided with a roughened or friction surface, have each a hub portion 41 depending therefrom on which is loosely mounted a sleeve 42. Each sleeve 42 is embraced by a split collar 43 from which projects the stem 100 44 of the thread guide 7. The two parts of each split collar are connected together by a clamping screw 45 in a well known manner, and by means of this construction it will be obvious that each collar 43 and its 105 thread guide may be adjusted vertically on the sleeve thereby to control the relative positions of the thread guide and the friction

wheel 30. The sleeve 42 is capable of being turned axially about the hub 41 and by this means the axial position of each thread guide 7 can be determined. The screw-threaded connection between each presser wheel and its rod 40 is secured by means of a spring arm 46 extending upwardly from the presser wheel and having its end 47 bent inwardly to engage the screw-threads 10 of the rod 40. Whenever during the downward movement of the frame 8 any of the friction wheels 30 are brought into contact with the conical or tapering face of the yarn mass *m*, said friction wheel will be 15 turned slightly and during such turning movement will be raised on the rod 40 in a manner well known to those skilled in the art, and the thread guides are thus gradually elevated as the thread mass is built up. 20 The advantage of being able to adjust the thread guide vertically relative to the friction wheels is to provide for building the thread mass of any desired diameter, for it will be obvious that since the spindle and 25 the corresponding rod 40 have fixed positions relative to each other each presser wheel 30 will always contact with the thread mass at a point where the diameter of the thread mass has a fixed length and, 30 therefore, if the yarn guide is lowered relative to the presser wheel the size of the bobbin will be increased, while if the thread guide is brought nearer the presser wheel the diameter of the thread mass will be less. 35 The device herein shown includes means for automatically separating the friction disk of any bobbin from the whirl 33 when the bobbin is of the proper size. As herein shown, each whirl has associated therewith 40 a lever 48 pivoted to the frame at 49 and adapted when raised to engage the under side of the friction disk 32 and separate the latter from the whirl. Each lever 48 has connected thereto a vertically-extending rod 45 89, the upper end of which extends through an aperture in a guiding plate 50 sustained by the frame 31. Each rod 89 is provided with a shoulder 51 which is adapted to engage a stop 93, as shown in Fig. 7, thereby 50 to hold the lever 48 depressed. A spring 52 secured at one end to each rod 89 and at the other end to said plate 50 tends normally to elevate the rod. Each rod 89 carries an adjustable arm 54 which is preferably situated at an angle, as shown best in Fig. 2, and is adapted to be engaged by the presser wheel 30 as the latter gradually rises. When the presser wheel is elevated sufficiently to engage the arm 54, the rod 89 will be thrown 55 backwardly thereby to disengage the shoulder 51 from the stop 93, and the spring 52 will then come into play to elevate the rod, thus bringing the lever 48 up against the under side of the friction disk and separating 60 the latter from the whirl. By making 65

the finger 54 adjustable vertically a thread mass of any desired length can be secured.

The spindles rotate at a uniform speed and therefore when the thread is being laid on the portion of the thread mass of larger diameter, as shown in Fig. 1, the thread will be drawn much more rapidly from the supply than when it is being laid on the bare spindle or the portion of smaller diameter. If a tension device capable of applying a uniform tension on the thread were used, the result would be that the thread would be wound tightly on the portion of large diameter, but would be wound more loosely on the portion of small diameter. In order to provide for laying the thread under a uniform tension throughout the entire thread mass I have provided a tension device adapted to apply a variable tension to the thread, the tension being greatest when the thread is being laid on the portion of the thread mass of smaller diameter and being least when the thread is being laid on the portion of larger diameter. The tension device herein shown comprises two grids or sets of fingers 17 and 18, the fingers of one set being adapted to play between those of the other set and the thread or yarn passing between the two sets of fingers. The fingers 17 are preferably fixedly sustained by the holder 60. The fingers 18 are secured to the stop 93 which is herein shown as a shaft journaled in the plate 50 and cut away on one side at the point where it engages the shoulder 51. The shaft 93 has extending therefrom an arm 61 to which is connected one end of a spring 20, the other end of the spring 20 being connected to a bar 21 extending across the top of the machine and playing in suitable guides 65. There is a similar tension device for each of the bobbins, and the springs 20 for all the tension devices are connected to the bar 21. This bar 21 has connected thereto a flexible connection 22, which passes over pulleys 23 and is connected to a small pulley 95 on a shaft 96. Said shaft also has fast thereon a pulley 97 to which a cord 98 is connected, said cord being also connected to one of the arms 13. The pulleys 95, 97 and 23 are omitted from Fig. 2 in order to avoid confusion. As the frame 8 rises the cord 98 will be drawn on thereby to turn the pulleys 97 and 95 and wind up the cord 22 on the latter pulley. This operation draws the bar 21 to the right and thus increases the tension on the springs 20, thereby causing the fingers 18 to bear on the thread with greater force and apply a greater friction thereon. It will thus be seen that the tension on the thread is greatest when the frame 8 is in its elevated position with the thread being wound on the portion of small diameter and is least when the frame is in its lowered position with the 130

thread being wound on the portion of larger diameter, as shown in Fig. 1. By means of this construction the thread will be laid uniformly compact throughout the thread mass 5 and a much firmer and better thread mass will result.

I have also provided means for stopping the operation of any spindle whenever its thread breaks. The flat surface 99 on the 10 stop or shaft 93, against which the shoulder 51 has engagement, is situated diametrically of the shaft and said shoulder normally engages said surface at a point in the axial line of the shaft. As a result the pressure 15 of the shoulder against said surface 99 does not have any tendency to turn the shaft and therefore does not affect the tension on the thread. If the thread breaks, however, the spring 20 and weight of the fingers 18 will 20 cause said shaft 93 to turn, as shown in dotted lines Fig. 7, thus carrying the flat surface 99 into a sufficiently inclined position so that the shoulder 51 will slide off therefrom whereby the spring 52 will come into 25 play to lift the rod 89 and stop the spindle.

The embodiment herein shown is the preferred embodiment, but it will be understood that many changes in the various parts might be made without departing from the 30 invention.

Having fully described my invention, what I claim as new and desire to secure by Letters Patent is:—

1. In a winding machine, the combination 35 with a rotary spindle, of means to wind thread thereabout after the manner of filling wind, a tension device through which the thread passes, said tension device having provision for applying a tension at all times 40 to the yarn, and means to cause said tension device to have a greater frictional engagement with said thread when the latter is laid on a portion of the thread mass of smaller diameter, than when it is laid on a portion 45 of the thread mass of larger diameter.

2. In a winding machine, the combination 50 with a rotary spindle, of means to wind thread thereabout after the manner of filling wind, a tension device comprising two 55 members between which the thread passes and which have at all times a sufficient frictional engagement with the thread to give the proper pressure thereto, and means to cause said members to have a greater frictional engagement with the thread when the latter is laid on a portion of thread mass of smaller diameter than when it is laid on a portion of the thread mass of larger diameter.

60. 3. In a winding machine, the combination with a rotary spindle, of a thread guide, means to give the thread guide a movement longitudinally of the spindle for winding

the thread thereabout, a tension device comprising two members which have a continuous frictional engagement with the thread thereby to apply a tension thereto at all times, and means to cause said members to have a greater frictional engagement with the thread when the thread guide is at one 65 end of its traverse than when the thread guide is at the other end of its traverse.

4. In a winding machine, the combination with a rotary spindle, of a thread guide, means to give the thread guide a movement 70 longitudinally of the spindle for winding the thread thereon after the manner of filling wind, a tension device comprising a set of fixed fingers, a rock-shaft carrying a set of movable fingers which play between the 75 fixed fingers, the thread to be wound passing between said sets of fingers, a spring acting on said rock shaft to cause the movable fingers to apply at all times a tension 80 on the thread, and means acting through the spring to increase the tension when the thread is being wound upon the portion of the thread mass of smaller diameter.

5. In a winding machine, the combination 90 with a rotary spindle and a rising and falling frame carrying a thread guide, of a tension device comprising a set of fixed fingers, a rock shaft carrying a set of movable fingers which play between the fixed fingers, the thread to be wound passing between 95 said sets of fingers, means for causing said two sets of fingers to apply a tension at all times on said thread, and means to increase this tension when the frame is in its elevated position.

6. In a winding machine, the combination 100 with a rotary spindle and a rising and falling frame carrying a thread guide, of a tension device comprising a set of fixed fingers and another set of pivoted fingers, a spring 105 acting on the pivoted fingers, and means to apply a greater tension to the spring when the frame is in its elevated position than when it is in its depressed position.

7. In a winding machine, the combination 110 with a plurality of rotary spindles and a rising and falling frame carrying thread guides therefor, of a tension device for each spindle comprising a set of fixed fingers and a set of pivoted fingers, a bar yieldingly 115 connected to all the pivoted fingers, and a flexible connection between said bar and said rising and falling frame.

In testimony whereof I have signed my name to this specification in the presence of 120 two subscribing witnesses.

ANKER PETERSEN.
